UNITED STATES PATENT OFFICE.

JOHAN ROBERT DEVOLD, OF LYSAKER, NEAR CHRISTIANIA, NORWAY.

MEANS FOR HAULING UP BOATS.

No. 893,610.

Specification of Letters Patent. Patented July 21, 1908.

Application filed February 1, 1908. Serial No. 413,867.

To all whom it may concern:

Be it known that I, JOHAN ROBERT DEVOLD, a subject of the King of Norway, residing at Lysaker, near Christiania, Norway, have invented certain new and useful Improvements in Means for Hauling Up Boats; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to means for facilitating the hauling up of boats. Heretofore boats, such as motorboats, etc., have been hauled up on rails or cradles running parallel with the axis of the boat. On shores exposed to the weather and high seas especially on steep shores, this mode of hauling up boats is connected with difficulties and heavy boats such as motor boats (now much used by the fishing men) could not possibly be hauled up in this manner under circumstances as above without damage to the boat.

My invention is based upon hauling up the boat in a transversal direction and consists in suitable means for this purpose comprising a suitably constructed cradle or truck.

In the drawing Figure 1 shows a side view of the general arrangement of the device, Fig. 2 and Fig. 3 are respectively horizontal, plan and side view at a larger scale, the middle part being broken away; Fig. 4 is a detail view.

On the shore is fixed two or more rails A, running down into the water. A cradle or truck B runs on these rails the rollers C of the same having preferably bearings with bent lower ends D, as shown in Fig. 4, thereby preventing the cradle from floating up from the rails when lowered down into the water. The truck is so constructed, that when it is submerged, a slanting wall or knees B' will prevent a boat lying as shown in Fig. 1 from being taken outwards by the waves. In bad weather therefore, when a boat is brought inside of these knees, which will be visible above the water, the cradle may speedily be hauled up out of the water, whereupon the boat may be suitably blocked up before it is hauled further.

The hauling device may consist of a beam or shaft E journaled in a suitable frame F

and provided with a wormwheel G, with which meshes a worm G' on a crankshaft H with removable crank P. Parallel with the crankshaft H is journaled another crankshaft 60 R, provided with a large gearwheel O meshing with a small gearwheel N on the shaft H. When the crank P is placed on this shaft the shaft or beam E may be turned with great speed.

From the shaft E to the cradle runs a rope I, it being laid over three pulleys K on the cradle and over two pulleys L on the foot M of the frame F. By carrying the rope in this manner it will always adjust itself.

Claims.

1. A device of the character described, comprising the combination with ways extending into the water, of a cradle adapted to support and retain a boat broadside, and mechanism for hauling the cradle and boat broadside on the ways.

2. A device of the character described, comprising the combination with inclined ways or rails extending into the water, of a cradle provided with means for supporting and retaining a boat broadside, and mechanism for hauling the cradle and boat broadside on the ways.

3. A device of the character described, comprising the combination with inclined ways, of a cradle provided with chocks or blocks forming a saddle upon which a boat may rest transversely, and mechanism for hauling the cradle and boat broadside on the ways.

4. A device of the character described, comprising the combination with inclined ways extending into the water, of a cradle provided with the oppositely inclined blocks 95 B' B' between which a boat may rest transversely on the cradle, and mechanism for hauling the cradle and boat broadside on the ways.

5. A device of the character described, comprising the combination with inclined rails extending into the water, a cradle having arms embracing the rails, oppositely inclined blocks carried by said cradle, and mechanism for hauling the cradle on the rails.

In testimony that I claim the foregoing as my invention, I have signed my name in presence of two subscribing witnesses.

JOHAN ROBERT DEVOLD.
